UNITED STATES PATENT OFFICE.

HARLEIGH GILLETTE, OF HIGHLAND PARK, ILLINOIS.

ELECTRIC GATE.

SPECIFICATION forming part of Letters Patent No. 442,114, dated December 9, 1890.

Application filed July 19, 1890, Serial No. 359,313. (No model.)

To all whom it may concern:

Be it known that I, HARLEIGH GILLETTE, of Highland Park, in the county of Lake and State of Illinois, have invented certain new and useful Improvements in Electric Gates, of which the following is a true specification, reference being had to the accompanying drawings, forming a part thereof.

This invention relates to gates for railway-crossings, drawbridge-approaches, &c., to be worked by means of the electric current; and it consists of improvements in the electrical circuit closing and breaking devices, whereby the motor is started and automatically stopped upon the gate-arms reaching either a lowered or raised position.

Figure 1 is a side view of the motor-circuit-closing device with the circuits open, and Fig. 2 shows the same with the circuits closed. Fig. 3 is a top view of the motor-box and circuit-closing mechanism. Fig. 4 is a sectional view of the circuit-closing device in the plane $x x$, Fig. 1. Fig. 5 is a plan of the gate-post mechanism. Fig. 6 is a plan of the complete gate as adapted to railway-crossings. Fig. 7 is a view in perspective of the post-supported conductor for the magnet-circuit. Fig. 8 is a detail section of the post-head, and Fig. 9 shows the method of making electrical connection with the same from the engine.

In describing my invention I begin with the motor-box O, a detailed top view of which is shown in Fig. 3. This box, built either above the ground or sunk partly below the surface, as convenience dictates, contains the electric motor and the entire electrical apparatus needed to operate the gate, with the exception of the battery or other generator, which is placed at a distance and connected thereto by wires in the usual manner.

From the motor-box O the power is transmitted to the four gate-posts (see Fig. 6) by means of the main shaft B and the two shafts C C. These latter are mechanically connected to B by means of two worms, one having a right and the other a left screw, which worms are affixed upon the shaft B, meshing with cogs upon the said shafts C C. As shown in Fig. 6, these shafts C C cross the railway-bed beneath the rails and are journaled in ordinary bearings affixed to the cross-ties. The

two ends of each are provided with small cogs, which mesh with larger wheels within the four gate-posts. Turning to Fig. 5, it is seen that these large wheels are provided with a 55 crank mechanism, by means of which the gate-arm is alternately raised and lowered by the forward or positive motion of the motor and power-transmitting mechanism. The details of this crank mechanism are more fully 60 set forth in my application for a patent on electric gates filed March 24, 1890, Serial No. 345,082.

Bearing in mind that the four gate-arms are both lowered and raised by the same forward or positive motion of the motor, it can be readily understood that it becomes necessary to break or shut off the motor-current at two different positions of the gate-arms. Thus after the motor has been started to close the gate 70 the circuit must be broken and the motor stopped when the arms have reached their horizontal or lowest extreme; and, again, after the motor has been restarted and the gate-arms raised the circuit must be rebroken and 75 the motor stopped at the instant the said arms have reached an upright or vertical position.

Returning to the motor-box, I connect the motor-shaft A direct to the main shaft B by a pair of ordinary cogs, as shown in the drawings. Upon the shaft B and within the motor-box is also affixed a worm W, which serves the sole purpose of operating the automatic cut off device. This worm meshes with an ordinary train of cogs for suitably reducing 85 the motion, the last member of which E is provided with a short oblong slot f² about half an inch long running near to and parallel with its periphery, and carries a shaft whereon is journaled a tubular journal-box 90 L, having affixed thereto three small parallel disks, one of which F' is provided with a pin f', which fits within the aforesaid slot f². This arrangement gives the three disks an independent play of about one-fourth of an 95 inch and mechanically connects them to the motor.

The three parallel wheels or disks rigidly affixed to their journal-box, as above mentioned, constitute the combined circuit closing and breaking device, the details of which are as follows:

Referring to the drawings, Fig. 4, the first or left-hand disk F' serves simply to carry the pin f', whereby the mechanical connection is made with the cog-train, as aforesaid. The second or center disk F consists of a circular plate of ordinary metallic conducting material inlaid with a small piece of hard rubber or other insulating material at the point b of its periphery, and two metallic spring-conductors a' and a² touch its said periphery at two diametrically-opposite points. These spring-conductors are in the electric circuit, joining the motor with the generator. On looking at the drawings it can be readily perceived that upon every semi-revolution of the disk F the electrical connection between the points of the brushes a' and a² will be broken by the insulated part b, while after the connection is thus broken a very slight forward movement of the said disk F will serve to carry the insulated part beyond the point of the spring-conductor, recomplete the connection, and consequently restart the motor. Should the disk be closely connected to the motor mechanism this would be impossible without moving forward the whole apparatus; but as the pin f' within its slot f² allows a limited independent motion to the disks a very slight impulse will be sufficient to turn the disk forward and recomplete the motor-circuit. The motor thus being started, the pin f' shortly after catches against the opposite side of its oblong slot, and is carried forward, together with the three disks, until the insulated point b of the conducting-disk F is brought under the opposite brush, when the motor-circuit is again automatically broken and the motor stops.

The third or right-hand disk G is made in the form of a ratchet-wheel and provided with a ratchet-catch pivoted upon the end of a lever composed of soft iron, the opposite or fulcrum end of the same being hinged to the frame-work by any suitable means. This soft-iron lever H constitutes the armature of an ordinary electro-magnet I, securely fastened in position, as shown in Figs. 1 and 2. Thus, on looking at the said Figs. 1 and 2, it is apparent that when the magnet I is energized by an electric current the lever-armature H will be at once attracted, carrying with it the ratchet-disk G, and thereby also moving forward the parallel conducting-disk F sufficiently to recomplete the motor-circuit, as aforesaid.

Having thus described the several parts, their action can be easily comprehended.

To summarize, supposing the motor-circuit to be open and the motor-circuit wheel in the position shown in Fig. 1, the circuit of the magnet I on being closed energizes the said magnet and draws to it the lever-armature H. This action turns the ratchet-wheel G, together with the parallel motor-circuit-closing wheel F to the extent of the independent motion allowed by the pin f' within its slot f², which is sufficient to carry the in-

sulated part b beyond the point of the brush a', and thus complete the motor-circuit, as shown in Fig. 2. The motor-circuit being closed, the mechanism is operated and the gate is lowered, the brushes a' a² meanwhile retaining a sliding connection with the conducting-wheel F until the insulated part b is brought beneath the brush a² to break the circuit at the instant the gate-arms have reached their extreme horizontal position. On the magnet-circuit being again closed the operation of the lever-armature, ratchet-wheel, &c., is repeated and the motor-circuit reconnected, to remain so until the gate-arms are raised and the circuit again automatically broken.

The magnet I is provided with one or more circuits with circuit-closers for same and an electric generator. In the case of bridge-gates, or whenever the gate is to be worked from a stationary operating position, the connection is made by the usual form of push-button or other well-known circuit-closers; but when the connection is to be made from a moving train I use the means illustrated in Figs. 7, 8, and 9. This consists of a conducting-rod J, supported on insulated posts arranged parallel with the track, the ends of which are depressed or inclined downward, as shown in the drawings, and a hinged conductor L', carried upon the locomotive and manipulated by the engineer. Thus, as the train approaches with the said hinged conductor in a horizontal position, the projecting end of the same strikes the inclined portion of the rod J with a sliding contact and completes the circuit from the said rod J, through the hinged conducting-lever L' and the locomotive driving-wheel to the rails R, which act as a return-conductor. By lifting up the lever before reaching the conducting-rod J the engineer can prevent the completion of the circuit and the consequent closing of the gate, and thus retain control of the same during the entire time that the engine is passing alongside the said rod J, which latter can be extended parallel with the track for an indefinite distance, if desired.

The electric current for operating these gates when the same are arranged in series is generated by dynamo and transmitted by wire carried upon the regular track telegraph-poles, including within its circuit as many gates as are economically practicable, which gates are arranged either directly upon or connected by shunt circuits with the main circuit. In isolated cases I use an ordinary storage or secondary battery, which is charged by one or more cells of a voltaic or primary battery. As the gate is operated intermittently, it is obvious that during the long intervals of inactivity the voltaic cell will charge the storage-battery sufficiently to furnish a strong though limited current when called upon to operate the gate, and under the circumstances will answer all the purposes of a more powerful primary battery.

In constructing the gate proper I do not

confine myself to the particular form shown. Many other well-known gates can be mechanically adapted to be operated under this electric system, the essential features of my invention being the means for closing and opening the motor-circuits. Any form of motor can be used that is adapted to control by an electro-magnet and circuit, as set forth.

I claim as my invention—

1. In an electric gate, the combination, with the gate proper mechanically connected to an electric motor, with its circuit-generator and automatic circuit-breaker, of a revolving circuit-closer for said circuit, provided with a ratchet and an electro-magnet, the latter being provided with a lever-armature carrying a pawl which acts upon the said ratchet, together with a generator, circuit, and circuit-

closer for the electro-magnet, substantially as specified.

2. In an electric gate, the combination, with the gate proper mechanically connected to an electric motor, with its circuit and generator, of a combined circuit-closer and automatic breaker for said motor-circuit joined loosely to the motor-operated mechanism by a pin and slot, and an electro-magnet provided with an armature mechanically connected to the said circuit-closer, together with a generator, circuit, and circuit-closer for the electro-magnet, substantially as specified.

HARLEIGH GILLETTE.
